UNITED STATES PATENT OFFICE.

ROBERT Y. WATSON, OF TAFT, CALIFORNIA.

TUBING-CATCHER.

1,193,091.

Specification of Letters Patent. Patented Aug. 1, 1916.

Application filed April 10, 1915. Serial No. 20,477.

To all whom it may concern:

Be it known that I, ROBERT Y. WATSON, a citizen of the United States, residing at Taft, in the county of Kern and State of California, have invented new and useful Improvements in Tubing-Catchers, of which the following is a specification.

This invention relates to a tubing catcher.

In the operation of oil wells it sometimes happens that a considerable length or section of tubing drops into the well, this being caused by a parting of the tubing, stripping of thread, or the like. A lost section of tubing causes any amount of trouble, cost and loss of time as it sometimes requires months of work with fishing tools and the like before the lost sections are secured and removed.

One of the objects of the present invention is to provide a tubing catcher on which is mounted a plurality of gripping jaws; and to provide means for automatically and instantly expanding same to engage the main well-casing the moment a section of tubing parts and drops.

Further objects will hereinafter appear.

The invention consists of the parts and the construction and combination of parts as hereinafter more fully described and claimed, having reference to the accompanying drawings, in which—

Figure 1 is a side elevation of the tubing catcher. Fig. 2 shows the application of the invention. Fig. 3 is a central, longitudinal section on line 3—3, Fig. 1. Fig. 4 is a cross section on line 4—4, Fig. 1.

More particularly described, A indicates the main exterior casing of an oil well, 2 the tubing, 3 the pump barrel which is secured to the lower end of the tubing, 4 the piston or plunger, 5 the piston-rod, 6 the strainer pipe which is screwed into the intake end of the pump barrel, and 7 the tubing catcher in general which forms the subject-matter of the present invention.

The tubing catcher consists of a head 8 which is adapted to be screwed into the lower end of the strainer pipe, as indicated at 9. Formed integral with the lower end of the head or otherwise secured to same is a downwardly extending rod 10, and slidably mounted on the rod is a tube 11, the upper end of which is flanged, as at 12, to form a seat for a pair of gripping members 13. Mounted on the lower end of the rod is a nut, and interposed between said nut

and the upper flanged end of the tube is a coil spring 15. This spring forms a resilient seat for the tube and also for the gripping members, as they are directly supported by 60 the flanged end of the tube.

Each side of the head is provided with an inclined groove 16 which is dovetail shaped in cross section, and each gripping member is provided with a lug 17 which fits the adjacent groove. The gripping members are thus slidably mounted on the head proper and the head at the same time serves as a wedge to force the gripping members outwardly into engagement with the interior 70 surface of the well casing A. The gripping members are preferably segmental shaped in cross section to correspond with the inner surface or face of casing A and their outer faces are provided with teeth, such as indicated at 18, to form an efficient grip.

In operation, referring to Fig. 2, it will be seen that the tubing catcher is mounted below all the suspended parts, such as the tubing, pump strainer, pipe, etc. It is thus 80 in position to stop the parts from falling or dropping farther down into the well if any of the parts become detached or accidentally dropped. The tension of the spring is not sufficient to raise the tube and wedges 85 sufficiently to bring these into engagement with the casing but merely acts as a cushion or resilient support for same, which tends to project the tube and wedges in an upward direction if the head 8 and rod 10 90 should suddenly drop.

Referring to Fig. 3, it can be seen that a quick downward movement of the head 8 will cause it to pass down between the gripping members 13 like a wedge and force 95 these outwardly into gripping engagement with the interior face of the main well casing A. The lost parts can thus only drop, at the most, a few inches before they are caught by the expanding or projected action of the gripping members. The gripping members 13, together with the tube 11, act as floating members, with relation to head 8 and rod 10, first, by reason of the resilient cushion or support provided by 105 spring 15, and, second, by the action of the oil entering the interior of tube 11 and acting interiorly and exteriorly on flange 10a. A quick downward movement of head 8, when the tubing parts or when it is accidentally dropped, will thus cause the oil to 110 strike against the flange 10a and automatically

cally and instantly force the gripping members outwardly into engagement with the well casing as these will practically remain stationary compared with the speed or falling movement of head 8 and the superposed attached parts.

The materials and finish of the several parts of the tubing catcher are such as the experience and judgment of the manufacturer may dictate.

I wish it understood that various changes in form, proportions and details of construction may be resorted to within the scope of the appended claims and that I do not wish 15 to limit myself to the specific design and construction here shown.

Having thus described my invention, what I claim and desire to secure by Letters Patent is—

20 1. A tubing catcher comprising a head, a gripping member carried by the head for projection therefrom, and a resiliently mounted tubular member open at its lower end and substantially closed at its upper end, said tubular member serving as a means for projecting the gripping member and being constantly unrestrained for operation by the resistance of a liquid when the tubing catcher is accidentally dropped therein.

25 2. A tubing catcher comprising a head, a pair of gripping members slidably mounted on the head, a tube slidably mounted with relation to the head and free of the gripping members, a flange on the upper end of the tube forming a support for the gripping members, and a resilient support for the tube, freely supporting the same in normal

position, said tube being always free for sliding relative to the head.

3. A tubing catcher comprising a head, said head having an inclined groove formed on each side, a gripping member slidably mounted in each groove, a freely movable tube slidably mounted with relation to the head, a flange on the upper end of the tube forming a support for the gripping members and an abutment for the liquid to act upon when the same is dropped and a resilient support freely mounting the tube when the latter is in normal position.

4. A tubing catcher comprising a head, said head having an inclined groove formed on each side, a gripping member slidably mounted in each groove, a downwardly extending solid rod on the lower end of the head, a tube slidably mounted on the rod, a flange on the upper end of the tube forming a direct support or seat for the gripping members, and a spring on the rod forming a support for the tube.

5. A tubing catcher comprising a head, a gripping member carried by the head for projection therefrom, and means movable relative to the gripping member and head and operable solely by the resistance of a liquid in dropping therein for projecting the gripping member from the head.

In testimony whereof I have hereunto set my hand in the presence of two subscribing 70 witnesses.

ROBERT Y. WATSON
